Primary Examiner — Phillip S Hyder(74) *Attorney, Agent, or Firm* — Crossley & Stevenson IP Law(57) **CLAIM**

The ornamental design for an extension handle for a wrench, as shown and described.

DESCRIPTION

FIG. 1 is a front elevation view of an extension handle for a wrench showing my new design, the opposite side being a mirror image of the shown;

FIG. 2 is a left side elevation view thereof;

FIG. 3 is a right side elevation view thereof;

FIG. 4 is a top plan view thereof;

FIG. 5 is a bottom plan view thereof;

FIG. 6 is an isometric view thereof; and,

FIG. 7 is a cross-sectional view taken along line 7-7 of FIG. 4. The broken lines in FIG. 6 of the drawings depict a combination end wrench as environmental subject matter only and form no part of the claimed design.
